ATTORNEY

UNITED STATES PATENT OFFICE.

MARGERET E. KILLEAN, OF SAN FRANCISCO, CALIFORNIA.

BLOOMERS.

1,109,231.

Specification of Letters Patent.

Patented Sept. 1, 1914.

Application filed September 8, 1913. Serial No. 788,724.

To all whom it may concern:

Be it known that I, MARGERET E. KILLEAN, a citizen of the United States, residing in the city and county of San Francisco and 5 State of California, have invented new and useful Improvements in Bloomers, of which the following is a specification.

This invention relates to a garment, and particularly pertains to bloomer drawers.

10 It is the object of this invention to provide bloomer drawers of the closed style which will not restrain movements of the body and limbs when worn and in which draw-strings and continuous elastic bands 15 are dispensed with.

A further object is to provide a garment of the above character which is close fitting so as to be worn under fitted skirts without forming unsightly bulges or creases in 20 the latter, and which garment can be readily put on and removed.

The invention primarily resides in a garment having continuous front, seat and leg portions, with a back portion continuous 25 with the front portion at the sides and slashed vertically on each side of its center to form a flap and an opening closable thereby above the seat, means for rendering the flap laterally elastic, and means for fastening the flap to the sides of the opening.

The invention further consists of the parts and the construction and combination of parts as hereinafter more fully described and claimed, having reference to the accompanying drawings, in which—

Figures 1 and 2 are front and back views, respectively, illustrating the garment as worn. Fig. 3 is a perspective view of the garment from the back. Fig. 4 is a detail 40 plan view of the upper edge of the flap. Figs. 5 and 6 are unassembled views of the back and front portions, respectively, of the left half of the garment; the patterns for the garment corresponding to the figures 45 illustrated in the views.

In carrying out the present invention, the main portion of the garment is made with four pieces of any suitable fabric, designated as 1—2—3 and 4 in the drawings, and 50 particularly shown in Fig. 3; the pieces 1 and 2 forming the front portion and the pieces 3 and 4 forming the rear portion of the garment. The front pieces 1 and 2 correspond in outline with each other, except 55 that they are reversed to form right and left members which are stitched together along

the edges from *a* to *b*; the back pieces 2 and 3 likewise agreeing with each other and reversed to form right and left members which are stitched together along the edges 60 from *c* to *d*. The front pieces 1 and 2 are stitched to the rear pieces 3 and 4, respectively, along their outer edges from their upper edges at *e*, located at the waist-line, to a point at *f* a short distance above their lower edges *g*; the edges from *f* to *g* being hemmed to form slits 5 at the lower outer side of the leg portions of the garment, which are designed to extend to a point immediately below the knees of the wearer. 70 The front pieces 1 and 2 are also stitched along the inner edges *b* to *h* to the inner edges *d* to *i* of the back pieces 3 and 4, respectively; the edge *b*—*h* being gathered from *h* to *j* to bring the edge *g*—*h* to the 75 position indicated in dotted lines *k* in Fig. 6, and thereby form sufficient fullness 6 on the front lower ends of the leg portions to permit of free movement of the knees. A seam *e*—*f* will thus be formed on the sides of the 80 garment from the upper edge or waist-line to the knee, as shown in dotted lines in Fig. 3, and on the inside of the leg portions from *i*—*h* to the crotch *b*—*d*; a seam also extending from *a* at the center of the upper edge 85 of the front of the garment through the crotch *b*—*d* to the center *c* of the upper edge of the back of the garment. It is manifest, however, that the parts just described may be woven in one piece or otherwise formed 90 according to the facilities of manufacture.

The essence of the present invention resides in forming the back portion of the garment at a point above the seat with a peculiarly constructed flap 7 which is formed 95 by a pair of parallel V-shaped slits 8 in the back pieces 3 and 4, extending from the upper edge thereof a short distance on each side of the center *c* to a point slightly above the seat. The flap 7 is formed with a pair of 100 spaced plaits 9, commonly termed box-plaits, which extend from the upper edge of the flap to a point well down on the seat portion of the garment on each side of the center and adjacent to the edges of the flap. These 105 plaits furnish the necessary fullness in the seat to permit free bending movement of the body.

A waist band 10 is stitched on the upper edges of the front and back pieces 1—2—3 110 and 4, and terminates at the slits 8; the upper edges of the front portions being con-

caved at the center and taken up by darts 11 on each side of the center to obviate fullness and insure a snug fit across the front and around the waist.

5 A gathered elastic tape 12 is stitched at intervals to the upper edge of the flap 7, to provide a yieldable or elastic tensioned portion in the waist-band; the flap 7 being gathered between the stitches connecting the 10 elastic tape thereto, as shown in Fig. 4, to permit extension of the elastic tape.

The side edges of the flap 7 are designed to be attached to the edges of the slits 8, and ordinary glove fasteners are provided for 15 this purpose. The studs 13 of the fasteners are secured to the body portion of the garment along the edges of the slits 8 and are spaced a suitable distance apart; the upper 20 studs being attached to the waist-band 10 adjacent to its ends. The caps or socket portions 14 of the fasteners are secured to the flap 7 on its inner face adjacent to its side edges, so that the fasteners will be concealed. Normally the side edges of the flap 25 7 will be spaced from the edges of the slits 8, but when the garment is worn the edges of the flap are drawn over in opposition to the tension of the elastic tape 12 and secured to the main body portion of the garment by 30 means of the fasteners 13—14. The elastic tape will then operate to tension the waist-band 10 to hold it snug around the waist and retain the garment in place.

The lower ends of the leg portions are to 35 be secured below the knees of the wearer and are provided with gathered elastic tapes 15 which extend from one side of the slits 5 along the bottom edges of the leg portions to the opposite side of the slits. The slits 5 40 are drawn together in opposition to the elastic tapes 15 and fastened by glove clasps or other devices 16, after the garment is put on; the clasps 16 being unfastened in putting on and removing the garment to facilitate

passing the lower ends of the leg portions over the feet.

45 The crotch portion of the garment is reinforced on the interior by a pad 17, which is indicated in broken lines in Fig. 3, which pad may be permanently stitched in place 50 or may be a removable perspiration pad.

The garment hereinbefore described is preferably made of silk crêpe or other pliable fabric, and may be made very close fitting and yet permit of free bodily movement, by reason of the box-plaited back and flap, the elastic insert in the waist-band and the gathered fullness at the knees.

55 In some instances it may be desirable to form the back members 3 and 4 in one piece 60 so as to obviate a seam from points *c* to *d* in the center of the back, in which event such fullness as may exist will be taken up in the gathers at the upper end of the flap 7 and in the plaits 9.

65 Having thus described my invention what I claim and desire to secure by Letters Patent is:

In a bifurcated nether garment, a waist band having separated ends secured to the 70 upper edge of the garment, said waist band being formed of inelastic material, a flap connected to the seat, an elastic band at the upper edge of the flap directly connected to the ends of said flap, fastening means at 75 the ends of the waist band, and fastening means at the ends of the flap to engage with the first named fastening means, whereby said elastic band of the flap acts to tension the waist band and to draw same taut and 80 smooth.

In testimony whereof I have hereunto set my hand in the presence of two subscribing witnesses.

MARGERET E. KILLEAN.
